UNITED STATES PATENT OFFICE

2,654,908

CONVERTER FOR SUCTION CLEANERS

Harry B. White, Canton, Ohio, assignor to The
Hoover Company, North Canton, Ohio, a cor-
poration of Ohio

Application February 28, 1951, Serial No. 213,207

11 Claims. (Cl. 15—337)

1

This invention relates to suction cleaners and more particularly to a converter therefor for converting the cleaner from on-the-floor cleaning to off-the-floor cleaning.

Specifically, according to the present invention, a converter is provided with a forked end to straddle a belt pulley extending through the fan eye and to mate with the fan eye. A pair of shutters or closure plates are pivoted to the slotted end of the converter to close off the slot except for the space occupied by the pulley shaft. The shutters are connected by a linkage mechanism to a movable actuator, in the form of a converter latch adapted to be contacted by means on the cleaner as the converter is inserted, to first open the shutters or closure plates to permit the pulley to enter the slotted end of the converter and to thereafter close about the pulley shaft.

In one modification, the linkage mechanism is in the form of a single link connected to one of the shutters and gear means on the shutters so as to open and close the latter in unison.

Other objects and advantages of this invention will become apparent as the description proceeds when taken in connection with the accompanying drawing in which:

Figure 1 is a bottom plan view of one modification of a converter of this invention;

Figure 2 is a side view of a cleaner partly in section showing the converter of Fig. 1 in place;

Figure 3 is a bottom view of the converter of Fig. 1 showing how the shutters are opened during conversion;

Figure 4 is a side view of a cleaner partly in section showing a modified converter in place; and

Figure 5 is a bottom view of the converter of Fig. 4 as it is being applied to the cleaner.

Referring to Figs. 1, 2, and 3 the converter, generally indicated by the reference numeral 10, includes an upwardly inclined female fitting 11 for attachment to a male fitting on the end of a flexible hose, the opposite end of which is to be attached to any suitable cleaning tool.

The converter 10 also includes a flattened portion 12 for insertion into a converter passage 13 extending rearwardly from the fan eye 14 of the cleaner 15. The flattened portion has top and bottom walls 16 and 17 respectively. At its forward end the top wall is cut away at 18 to form an open ended lateral opening to mate with the fan eye 14 when the converter is fully inserted. At its forward end the bottom wall 17 is slotted at 19 to form a pair of legs 20 and 21

2

which straddle a belt pulley shaft 22 when the converter is fully inserted.

Pivoted at 23 and 24 to the underside of the wall 17, adjacent the rear end of the slot 19, are a pair of shutters or closure plates 25 and 26 having spaced notches 27 and 28 for receiving and closely surrounding the shaft 22. The shutters 25 and 26 have straight edges forwardly of the notches 27 and 28 which meet at line 29 when fully closed to close the forward end of slot 19. At their forward ends the shutters 25 and 26 are turned upwardly at 30 to coat with the bottom wall 31 of the fan chamber to substantially seal off the suction passageway 32 from the fan eye 14 when the converter is fully inserted.

The shutters 25 and 26 have mating teeth 33 and 34 between their pivot points 23 and 24 which forms a part of the linkage mechanism to open and close them in unison. One side of the flat portion 12 of the converter has a recess 35 formed therein to house an actuating rod 36 pivotally connected at its forward end to a lug 37 extending from the shutter 26 opposite the teeth 34 and at its rear end to a pin 38 on a converter latch 39 pivoted at 40 in the recess 35 of the converter tube. A spring 41 surrounds the pivot 40 and biases the latch 39 to the position shown in Fig. 1 to move the shutters 25 and 26 closed. The actuating rod 36 is bent out at 42 so as to pass through a slot 43 in a converter guide tube as the converter is inserted. The actuating rod 36 and gear teeth 33, 34 form the linkage mechanism between the latch 39 and the shutters to open and close them.

The slot 43 is formed by a lug 44 struck outwardly from the side wall of tube 70. The lug 44 has a cam surface 45 at its rear end to coat with the cam shaped end 47 of latch 39 to open the shutters 25 and 26 as the converter is inserted. The latch has a lateral shoulder 46 which engages behind a shoulder 48 on lug 44 to latch the converter in place when fully inserted. A cam surface 49 is provided on lug 44 to the rear of shoulder 46 for a purpose which will presently appear.

Operation of Figs. 1 to 3

When it is desired to convert to off-the-floor cleaning the end 11 of the converter is grasped and its forward end inserted into the guide tube 70 to the rear of converter passageway 13 and pushed forwardly. Just prior to the time that the shutters 25 and 26 reach the shaft 22 the cammed end 47 of lever 39 engages the cam 45 of lug 44 and pivots the lever 39 clockwise against

the bias of the spring 41 which will reciprocate the rod 36 and pivot the shutter 26 clockwise causing the mating teeth 34 and 33 to shift the shutter 25 counterclockwise to the position shown in Fig. 3.

As the converter is further inserted the cammed end 47 will ride over the shoulder 46 of lug 44 to latch the converter in place and the spring 41 will pivot the latch lever 39 counterclockwise to close the shutters 25 and 26 about 10 the shaft 22 and close the end of slot 19. The straight edges 29 of the shutters having met the notches 27 and 28 will close closely about the shaft 22.

It is to be noted from Fig. 2 that when the converter is fully inserted the open ended aperture 18 in the upper wall 16 of the converter tube exactly mates with the fan eye 14 and the ends of the legs 20 and 21 together with the upturned end 30 of the shutters 25 and 26 will substantially 20 seal the suction passageway 32 from the fan eye 14 whereby the entire suction produced will cause air flow through the converter 10.

When it is desired to reconvert to on-the-floor cleaning the latch lever 39 is depressed to raise the shoulder 71 above the shoulder 46 and the converter 10 merely pulled out of the converter passageway 13 and guide tube 70. As the converter is pulled rearwardly the cam 72 will be engaged by cam 47 of latch 39 and the shutters 25 and 26 30 opened sufficiently to clear the shaft 22.

The converter of Figs. 4 and 5 is substantially the same as that just described except for the actuating mechanism for the shutters and where the parts are the same they have been given the same reference numerals.

The shutters 25 and 26 have actuating links 48 and 49 pivoted thereto at 50 and 51 outside of their pivot points 23 and 24. The links 48 and 49 are received in a recess 52 in the bottom wall 17 of the converter and their rear ends pivoted at 53 and 54 to the legs of a latch lever 55 pivoted at 56 to the under wall 17 of the converter tube. A compression spring 57 acts between the bottom wall 17 and the lever 55 to bias the lever 55 to a 45 position to hold the shutters 25 and 26 closed as shown in full lines of Fig. 5.

The lever 55 has a cam end 58 which coacts with lugs 59 and 60 struck downwardly from the bottom wall of the guide tube 70, thereby forming a slot 61 between them for the passage of the lever 55 when the converter is inserted. One end of the lugs 59 and 60 is sloped to form cam surfaces 62 while the opposite ends are at right angles to form shoulders 63 to engage T-shaped 55 end 58 of the lever 55 and latch the converter in place.

Operation of Figs. 4 and 5

When it is desired to convert to off-the-floor cleaning the converter 10 is grasped and its forward end inserted in the guide tube 70 to the rear of the converter passageway 13. Prior to the time that the ends of the shutters 25 and 26 reach the shaft 22 the T-shaped end 58 of the lever 55 will engage the cams 62 of lugs 59 and 60 and pivot the lever counterclockwise as viewed in Fig. 4. That will in turn pull the rods 48 and 49 backwards and pivot the shutter 26 clockwise and the shutter 25 counterclockwise so as to permit the shaft 22 to enter the slot 19. When the T-shaped end 58 of lever 55 rides free of the lugs 59 and 60 behind the shoulders 63 the spring 57 will close the shutters to the position shown in Fig. 5 so that the ends of the T 58 will lie behind 70

the shoulders 63 and positively lock the converter in place.

When it is desired to remove the converter it is necessary to press upwardly on the lever 55 so as to move the shutters 25 and 26 to the dotted line position shown in Fig. 5.

During normal on-the-floor cleaning the fan 75 is driven by a motor housed within the appearance housing 76 and the cleaner propelled over the surface to be cleaned on rear wheels 77 and front wheels 77' by means of handle 78. At its forward end the cleaner is provided with a downwardly facing nozzle 81 in open communication with the suction passage 32. An agitator 82 is rotatably mounted within the nozzle and is driven by the belt 79.

The suction created by the fan 75 will draw the surface covering upwardly against the nozzle 81 and the dirt lodged therein will be removed by the combined action of the agitator 82 and the air being drawn therethrough by the suction created by the fan 75. The dirt laden air will be drawn through the suction passageway 32 and the fan eye 14 into the fan chamber and be discharged through the exhaust passageway into the dirt filtering bag 30.

When conversion is made, as above described, to off-the-floor cleaning the suction passageway 32 will be closed off from the fan eye 14 and the entire suction air stream will be drawn through the converter tube 10 from a cleaning tool connected thereto by means of a flexible hose.

From the foregoing it can be seen that this invention provides a converter having pivoted shutters for closing off the fan eye from the suction passageway except for the small clearance about the pulley in which the shutters are automatically opened and closed as the converter is inserted and removed.

While I have shown and described but two embodiments of my invention it is to be understood that those embodiments are to be taken as illustrative only and not in a limiting sense. I do not wish to be limited to the particular structure shown and described but to include all equivalent variations thereof except as limited by the scope of the claims.

I claim:

1. In a suction cleaner, a body having a fan therein and being formed with a suction nozzle having an agitator rotatably mounted therein, said fan including a fan eye communicating with said nozzle, a shaft for driving said agitator extending through said fan eye, a converter tube receiving passage in communication with said fan eye, a converter tube insertable into said converter passage so as to extend across said fan eye, a movable latch for latching said converter tube in said passage, said converter tube having an opening in one side wall in communication with said fan eye when fully inserted into said converter passage and a slot in its opposite side wall for receiving said shaft, a pair of shutters pivoted to said opposite wall of said converter in a position to close said slot except for notches to receive said shaft and being movable away from each other to permit passage of said shaft into said slot and link means connecting said shutters to said latch in such manner that releasing movement of said latch moves said shutters away from each other.

2. In a suction cleaner according to claim 1 including means on said body engageable with said latch for moving said shutters away from each other as said converter tube is inserted into

said converter passage and permitting closing movement of said shutters when said converter tube is fully inserted.

3. A converter for insertion into the converter passage of a suction cleaner of the type having a fan eye in communication with both a normal suction passage and a converter passage communicating with each other at the fan eye and with a pulley shaft extending through the fan eye into the junction of the two passages, said converter comprising a tube having a first wall adapted to face the fan eye and a second wall spaced therefrom, said first wall being formed with an opening adapted to mate with the fan eye and said second wall being slotted to form a pair of legs adapted to straddle the shaft when said converter is fully inserted into the converter passage, a shutter pivoted to the rear of each leg, said shutters each being formed with a notch adapted to close about the shaft and with mating faces closing said slot except for said notches when said converter is fully inserted, a latch adapted to cooperate with means on said cleaner for latching said converter in fully inserted position and means connecting said latch to said shutters operative to pivot said shutters outwardly to open said slot as said latch is moved into releasing position to permit removal of said converter from the converter passage.

4. A converter as in claim 3 in which said latch is adapted to be contacted by means on said converter passage to move said latch to releasing position and move said shutters outwardly to clear the shaft as said converter is inserted into the converter passage.

5. A converter according to claim 3 in which said shutters are geared to each other to move in unison as said latch moves to releasing position.

6. A converter comprising a tube having a first wall formed with an open ended opening to mate with the fan eye of a suction cleaner and a second wall spaced therefrom having a slot to form spaced legs to straddle the pulley shaft extending through the fan eye of the suction cleaner, a shutter pivoted to each of the inner edges of said legs adjacent the bight of said slot, said shutters having inner edges meeting on a line within said slot when in closed position, said edges being formed with mating notches to encompass the shaft extending through the fan eye, said first and second walls and said shutters being formed to close off the fan eye of a suction cleaner from the suction passageway thereof, a latch pivoted to said converter for locking it in the converter passage of a suction cleaner and linkage means connecting said latch to said shutters and operative to move said shutters away from each other as said latch is moved to unlatching position.

7. In combination, a suction cleaner having a fan eye communicating with a suction passage and with a converter passage and having a pulley shaft extending through said fan eye into the junction of said suction and converter passages, a converter tube insertable into said converter passage, said converter tube having first and second walls spaced from each other and lying between the pulley and fan eye when in inserted position, the inner end of said first wall being formed with an open ended port mating with said fan eye, the inner end of said second wall being formed with a slot to provide forked ends straddling said shaft, a shutter pivoted to the inner edge of each forked end adjacent the rear end of said slot and operable to mate with each other to close the end of said slot when in closed position, a latch pivoted to said converter tube, means on said cleaner engageable by said latch to lock said converter in said converter passage, and linkage means connecting said latch to said shutters and operable upon movement of said latch to unlatching position to move said shutters away from each other to open said slot.

8. The combination set forth in claim 7 in which the inner edges of said shutters are provided with mating notches to closely encircle said shaft.

9. The combination set forth in claim 7 including means on said cleaner engageable with said latch to move said latch to its open position as said converter tube is inserted into said converter passage and permitting closing movement of said latch as said converter tube reaches its fully inserted position in said converter passage.

10. The combination as set forth in claim 9 in which said latch is pivoted to said converter tube on an axis extending perpendicularly to said first and second walls, and said linkage means comprises a rod connecting said latch to one of said shutters and intermeshing means on said shutters between their pivots to cause them to move in unison.

11. The combination as set forth in claim 9 in which said latch is pivoted to said second wall on an axis parallel thereto and said linkage means comprising a pair of rods each connecting said latch to one of said shutters.

HARRY B. WHITE.
